UNITED STATES PATENT OFFICE

THOMAS A. BOWEN, OF BLACKSTONE, VIRGINIA.

RAILROAD-SWITCH.

SPECIFICATION forming part of Letters Patent No. 768,507, dated August 23, 1904.

Application filed February 25, 1904. Serial No. 195,282. ~~For model~~*To all whom it may concern:*

Be it known that I, THOMAS A. BOWEN, a citizen of the United States, residing at Blackstone, in the county of Nottoway and State of Virginia, have invented a new and useful Improvement in Railroad-Switches, of which the following is a specification.

My invention is in the nature of an improved automatic railroad-switch designed to be set into operation by the engineer or some other person on the train or by a switchman along the track, as when freight-trains are being operated over the same.

My improvements comprehend certain novel features in the switch mechanism and in the combination with the same, of a shifting lever with stand, light, and locking devices, which I will now proceed to describe with reference to the drawings, in which—

Figure 1 is a vertical cross-section through the track. Fig. 2 is a plan view, and Fig. 3 is an enlarged vertical section on line 3'3' of Fig. 2.

In the drawings, A A represent the main rails, and B B the switch-rails, of a railroad, and B' B' are the movable switch-tongues, which are pivoted at b' b' and at their tapered ends lie adjacent to the main rails on the inner sides of the same. The switch-tongues B' B' are firmly bolted at their tapered ends to a transverse slide-bar C, which extends under the rails and out to a lever-stand D, situated to one side of the track. The slide-bar C is formed in the middle with an enlargement, which has on its opposite sides sockets c c, which loosely receive the ends e e of two oppositely-placed cam-levers E E. These cam-levers (see Fig. 3) are elevated at their outer ends to a higher plane and are provided on their higher ends with flat and horizontal diamond-shaped cams e' e'. The levers E are fulcrumed at e between their ends and are also formed with overlapping wings e' e', which cover the sockets c in the slide-bar at all times irrespective of the position of the parts. This prevents the entrance of dirt or obstruction which might get into the joint and prevent the free operation of the parts. The diamond-shaped cams are designed to be struck by a

downward projection from the train—as shown, for instance, at a, Fig. 2—which projection is made adjustable up or down and is under the control of the engineer or some one on the train, so that when it is properly adjusted down to position it strikes one or the other of the cams. When such projection strikes a cam, it throws the lever E to one side, and as this has its end entered into the socket of the enlarged part of the slide-bar the slide-bar is slid longitudinally to one side or the other to shift the switch-tongues B' B'. By having a lever E upon each side and a diamond-shaped cam on each lever the slide-bar is shifted and the switch adjusted for trains going in either direction. The outer ends of the levers E are raised not only for the purpose of bringing the cams up to convenient engagement by the adjustable contacting mechanism on the train, but also for the purpose of giving room under the outer ends of the lever for a wheel or roller F, (see Fig. 3,) which causes the levers to move freely and quickly in response to the passage of the train. The slide-bar may be worked either with or without roller-bearings. When the switch is thrown from one side to the other, it is held up to its position against the rail by means of an upright lever G, carrying a weight g on its upper end. This lever is fulcrumed at g' to the stand D and at its lower end is loosely connected to the slide-bar C, so that when the lever G is thrown over to one side or the other its weighted end holds the switch to the position to which it is adjusted.

The stand has a rigid vertical post D' in the middle, which carries at its upper end a lamp D', and the lever G has attached to it on one side and moving with it a curved box H, which is open at the bottom and receives the lamp carried by the stationary post D'. At the ends of this curved box on each side are glazed windows h and h'. One end has white glass and the other end red glass, and when the lever G, with the curved box, is thrown to one side the white glass is brought opposite the stationary lamp, and when the lever and curved box are thrown to the other side the red glass is brought in front of the lamp, and in this

manner at night the safety and danger signals indicate the position of the switch. The weight of this glazed box co-operates with the ball on the end of the lever to hold it and the switch to its adjustment.

To protect the central parts of the switch-operating mechanism from cinders, snow, and other obstructions, a covering-plate 1 is attached to the slide-bar and is made to extend over and protect these parts. A hood J is attached to the lever G and extends over the switch-stand to protect its parts from the weather.

Having thus described my invention, what I claim as new, and desire to secure by Letters Patent, is—

1. A railroad-switch comprising two tapering tongues pivoted at their larger ends, a sliding cross-bar rigidly attached to said tongues and formed with an enlarged central portion with sockets on opposite sides of the same, two levers fulcrumed in the road-bed between the rails on opposite sides of the slide-bar and having their inner ends entered into the sockets of the slide-bar and cams mounted on the outer ends of the levers and adapted to be struck by a projection from the passing train substantially as described and for the purpose set forth.
2. A railroad-switch comprising two tapering tongues pivoted at their larger ends, a sliding cross-bar rigidly connected to the said tongues and formed with an enlarged central portion with sockets on opposite sides, two levers fulcrumed in the road-bed between the rails and having their inner ends entered into the sockets of the slide-bar, the outer ends of said levers being raised to a higher plane and bearing on the upper side a cam and on the

lower side a friction-roller as and for the purpose described.

3. In a railroad-switch, the combination with the switch-tongues and a sliding cross-bar connecting the same; of a lever fulcrumed in the road-bed about a vertical axis, said lever being loosely connected to the slide-bar and having its outer end raised and provided on the upper side with a cam arranged to be acted upon by the passing train and having on the lower side a friction-roller substantially as and for the purpose described.

4. A railroad-switch comprising two tapering tongues pivoted at their larger ends, a sliding cross-bar rigidly attached to said tongues and formed with an enlarged central portion with sockets on opposite sides of the same, two levers fulcrumed in the road-bed between the rails on opposite sides of the slide-bar and having their inner ends entered into the sockets of the slide-bar and their outer ends provided with cams, and a weighted upright lever fulcrumed outside the track and connected to the slide-bar to hold the same to the position to which it may be adjusted substantially as and for the purpose described.

5. The combination with a railroad-switch; of a stand located outside the tracks and having a stationary light-holder, an upright lever having its lower end connected to the switch and a signal-box attached to the lever and inclosing the light-holder and having differently-colored windows in its opposite ends substantially as and for the purpose described

THOMAS A. BOWEN.
